GRAIN THERMOMETER HOUSING

Forrest A. Dunn, Newton, Iowa

Application February 23, 1955, Serial No. 34,630

Term of patent 14 years

(Cl. D52—7)

FIG. 1

FIG. 2

FIG. 3

FIG. 4

Fig. 1 is a front perspective view of a grain thermometer housing showing my new design;

Fig. 2 is a side view thereof;

Fig. 3 is an end view from the top of Fig. 1; and

Fig. 4 is a rear perspective view thereof.

I claim:

The ornamental design for a grain thermometer housing, as shown.
